IMPROVED HORSE-COLLAR.

CHRISTIAN WOLF, OF RANTOUL, ILLINOIS.

Letters Patent No. 60,107, dated November 27, 1866.

SPECIFICATION.

TO ALL WHOM IT MAY CONCERN:

Be it known that I, CHRISTIAN WOLF, of Rantoul, in the county of Champaign, State of Illinois, have invented a new and improved Horse-Collar; and I do hereby declare that the following is a full, clear, and exact description thereof, reference being had to the accompanying drawings, making a part of this specification, in which—

Figure 1 is a front view of the collar.

Figure 2 is a view of the opposite side of the collar.

Figure 3 is a vertical section through the collar.

Figure 4 is an edge or side view of the collar.

Figure 5 is a modification of the stay block of figs. 1, 2, and 3, which is applied at the top of the collar.

Figure 6 is a perspective view of a trace-hook martingale ring and connecting staple of one side of the collar.

Figure 7 is a perspective view of the stay-block of fig. 5.

Similar letters of reference indicate corresponding parts in the several figures.

This invention relates to certain novel improvements on horse-collars, which are so constructed as to dispense with separate hames, the trace-hooks, rein-rings, and other parts belonging to hames, being secured firmly to the collar, and forming part of it. The nature of my invention consists in the application to a wooden horse-collar, which is suitably padded on that side which presses against the horse, of devices for adjusting the upper and the lower parts of the collar to fit horses of different size; said devices being adapted for sustaining the sides of the collar firmly in the desired position, as will be hereinafter described. It also consists in a novel mode of attaching the trace-hooks to the sides of the collar, whereby great strength and security are obtained, as will be hereinafter described.

To enable others skilled in the art to understand my invention, I will describe its construction and operation.

In the accompanying drawings, A A represent the two sides of the collar, which are made of wood, properly shaped to fit the neck of a horse, and padded on those sides which press upon the animal. The padding consists of pieces of leather B B, which are nailed on the collar sides A A, and stuffed in a suitable manner to prevent injury to the animal, and to protect him from the wooden parts. The shape of the collar resembles the well-known shape of the stuffed leather collar, with this exception: the stuffed leather collars have creases for receiving and keeping in place the hames, while in my collar, where hames are not used, such creases are not made. The upper ends of the side pieces A A are attached together by means of a hinge, a, which consists of two wide metallic plates jointed centrally between the two horns b b, and secured in place by means of rods or tangs a' a', which are formed on their hinge-plates, and which pass laterally through the horns b, and receive on their ends nuts c c, by means of which the upper ends of the sides A A are drawn tightly against a stay-block d, which is interposed between these sides just at the upper curve or arch of the collar. Instead of employing a stay-block, d, which has a tenon d' upon it, as shown in fig. 3, and which involves the necessity of carving the arched projections e e, on the wooden sides A A, these projections may be omitted, and arched blocks of the form shown in figs. 5 and 7 used instead of the pieces of the form shown in figs. 1, 2, and 3. The arched blocks g being made of different lengths, the upper part of the collar can be made wider or narrower, as may be required, by interposing a block of the proper length. The blocks g are confined in place between the upper end of the collar sides by the hinged rods and clamping nuts above described; and if desirable, said blocks may be secured to the hinged plates a by means of screws, or in any other suitable manner. A strap, D, is wound around the stay-block and hinge-plates, and buckled, so as to protect the neck of the animal from injury. The lower ends of the side pieces A A are connected together by means of a transverse adjusting screw, C, which passes loosely through a projecting ear, h, and is tapped through a corresponding ear, h'. These ears are formed on plates which receive and are rigidly secured to the lower ends of the side pieces A A, as shown in figs. 1, 2, and 3. The screw C has a head formed on one end for receiving a rod or a wrench for turning it, and thus contracting or expanding the lower part of the collar. The shoulders, which are formed on that part of the screw C which turns loosely in the ear h, prevent endwise movement of this screw, and consequently hold the lower ends of the collar sides firmly in the desired position. The rings j j, which are secured rigidly to the sides of the collar near the horns b b, are intended for receiving through them the reins. The hooks k k are intended as fastenings for the front ends of the traces, and the rings s s are used as a

means for attaching the martingales to the collar. The hooks and rings, *k* and *s*, are pivoted to the staples *E E*, the ends of which pass through the wooden side pieces, and receive on their ends nuts, as shown in 6. The nuts on the staples hold them firmly in place, and are recessed into the collar sides and covered by the padding *B*, so as not to injure the neck of the horse.

Having described my invention, what I claim as new, and desire to secure by Letters Patent, is—

1. Connecting the upper ends of the side pieces *A A* of a wooden collar together by means of a hinge *a*, and clamping-nuts *c c*, in combination with an interposed block for staying said parts *A A* laterally, substantially as described.
2. The leather strap *D*, applied to the upper part of the wooden collar, substantially as and for the purpose described.
3. Connecting the lower ends of the side pieces *A A* together by means of an adjusting screw *C*, substantially as described.
4. Connecting the trace hooks *k* and rings *s* to the wooden sides *A A* of the collar, by means substantially as described.
5. In combination with the wooden side pieces *A A*, and padding *B*, I claim the hinged clamp *a*, movable block *d* or *g*, and the adjusting screw *C*, all constructed and operating substantially as described.

CHRISTIAN WOLF.
